CLAIM

The ornamental design for footwear, as shown and described.

DESCRIPTION

FIG. 1 is a top, right side perspective view of footwear, showing the new design;

FIG. 2 is a right side view thereof;

FIG. 3 is a left side view thereof;

FIG. 4 is a front view thereof;

FIG. 5 is a rear view thereof; and,

FIG. 6 is a top view thereof.

Broken lines depict portions of the footwear that form no part of the claimed design. The crosshatch shading of regions in the figures represents a generic mesh pattern spanning such regions, and no specific mesh pattern is claimed.
